US0D1002578S

(12) **United States Design Patent** (10) **Patent No.:** **US D1,002,578 S**
(45) **Date of Patent:** **** Oct. 24, 2023**

(54) **ELECTRONIC DEVICE**

- (71) Applicant: **Amazon Technologies, Inc.**, Seattle, WA (US)
- (72) Inventors: **Sun Joo Han**, San Francisco, CA (US); **Giles David Matthew McWilliam**, San Francisco, CA (US)
- (73) Assignee: **Amazon Technologies, Inc.**, Seattle, WA (US)
- (**) Term: **15 Years**

(21) Appl. No.: **29/803,108**

(22) Filed: **Aug. 10, 2021**

Related U.S. Application Data

- (62) Division of application No. 29/654,619, filed on Jun. 26, 2018, now Pat. No. Des. 930,613.

(57) **CLAIM**

The ornamental design for an electronic device, as shown and described.

DESCRIPTION

FIG. 1 is a top perspective view of an electronic device; FIG. 2 is a bottom perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the electronic device that form no part of the claimed design.

1 Claim, 8 Drawing Sheets
